UNITED STATES PATENT OFFICE.

EDWARD H. PALMER AND WILLIAM S. KINSLEY, OF READING, MASSACHUSETTS; SAID KINSLEY ASSIGNOR TO SAID PALMER; EMILY M. PALMER AND HAROLD V. PALMER, BOTH OF READING, MASSACHUSETTS, AND WALTER H. ROBERTS, OF MALDEN, MASSACHUSETTS, EXECUTORS OF SAID EDWARD H. PALMER, DECEASED; SAID EXECUTORS ASSIGNS TO EMILY M. PALMER AND HAROLD V. PALMER, INDIVIDUALLY.

CALCULATING MECHANISM.

1,212,249.

Specification of Letters Patent.

Patented Jan. 16, 1917.

Application filed August 3, 1912. Serial No. 713,142.

To all whom it may concern:

Be it known that we, EDWARD H. PALMER and WILLIAM S. KINSLEY, citizens of the United States, and residents of Reading, in 5 the county of Middlesex and State of Massachusetts, have invented certain new and useful Improvements in Calculating Mechanism, of which the following is a specification.

10 This invention relates to calculating apparatus especially designed for effecting subtraction by means of addition, the present invention including features divided from our application 533,443, filed December 15, 1909.

15 The mechanism has been especially designed for operation simultaneously with a typewriting machine, under the control of the latter, for indicating totals of figures 20 which are being written upon a sheet by the typewriting machine.

25 The object of the invention is to provide improvements particularly relating to the operation of effecting subtraction by means of addition, which requires the addition of a 1 to the "cents" column, the prevention of carrying, beyond the higher value enumerated, and the reversal of the order of the digits; for instance, if a 6 is to be subtracted, 30 3 is added, and if a 5 is to be subtracted 4 is added, and if a 9 is to be subtracted there shall be an actuation of a lever which will do no adding but which will actuate the mechanism to print a "9." This method provides for the addition of the complement of 35 9 (the difference between 9 and the real amount to be subtracted) and the prevention of carrying as stated.

40 The invention consists in the construction and combination of parts substantially as hereinafter described and claimed.

45 Figure 1 is a plan view of enough of the mechanism to illustrate an embodiment of our invention which provides for subtraction; Fig. 2 represents a section on line 2-2 of Fig. 1; Fig. 3 represents a section on line 3-3 of Fig. 1; Fig. 4 is a detail elevation of the devices shown at the lower left-hand corner of Fig. 1; Fig. 5 represents a section 50 on line 5-5 of Fig. 4; Fig. 6 represents a

section on line 6-6 of Fig. 5; Fig. 7 represents a section on line 7-7 of Fig. 1.

Similar reference characters indicate the same or similar parts in all of the views.

Before explaining the structure and operation of the mechanism especially claimed herein, we will briefly refer to some of the co-acting parts which are the same as, or similar to, the mechanisms for the same purpose described in our said application 533,443.

A suitable base 5 having side frame members 6 supports a shaft 9^a having arms 10^a, 10^b, one or more springs 13 being provided to normally hold said shaft in such position that its arms will remain in proper normal positions. The frame also supports a bar 151 (Fig. 1) to which lever members 19 hereinafter described are pivoted. Finger disks 16, 16^a and 16^b are carried by the outer ends of lever members 17^a pivoted on a rod 106^a and held in their normal upper positions by springs 17^b (Fig. 2). The levers 17^a constitute the manually operated key levers. Levers 19 are pivoted at 15 and extend horizontally backwardly and nearly to the shaft 9^a, said levers 19 having studs 20 and 29 extending from opposite sides thereof.

The levers referred to are arranged in 80 groups of four, as hereinafter more fully explained, while in the application 533,443 referred to, the mechanism remaining as the subject matter thereof shows such levers in groups of three.

85 Slides 31 suitably mounted on the base have rack arms 41 pivotally connected to their forward ends (Fig. 1) and actuating ratchet pinions 45 carrying indicator disks 46 mounted on spindles 47, the numerals of the indicating disks showing through apertures 48 in a cover plate 49. Slides and their rack arms are actuated as hereinafter described.

90 The mechanism which provides for carrying from one indicator to another includes a series of pivoted arms or bars 51 having cam portions 51^a and stop shoulders 51^b, stop pins 58^a being located to limit the movements of said arms 51. One 95

end of each arm 51 has a carrying arm 54 pivoted to it and the other end has a detent arm 55 pivoted to it. Springs 61 are connected to the pivoted arms 51 so as to normally hold the detent arms 55 against stop pins with the ends of said arms in the path of movement of ratchet pins carried by the ratchet pinions 45 so that after a ratchet pinion has been actuated from 1 to 9, a further step will disengage the detent arm 55 and cause spring 61 to oscillate its pivoted arm 51 so that a tooth of arm 54 will advance the next ratchet pinion to the left one tooth.

In Fig. 1 we illustrate simply end portions of two shafts 70 and 119, which are mounted in the frame, said shafts having pins which co-operate with the mechanism so far described in returning the bars 51 to normal position, and to engage the detent 55 at certain times. As the mechanism including said shafts 70 and 119 forms no part of the present invention, further description thereof herein is not necessary.

The slides 31 are provided with pins 181 which are engaged by a detent bar 180 having arms 182 connected to a plate 197. Said plate 197 is suitably mounted to reciprocate in a horizontal plane, said plate having rack teeth 200 engaged by toothed segments 201 which are connected to the rock-shaft 9^a. When the rock-shaft oscillates it imparts forward and backward movements to the plate 197 and through the arms 182 to the bar 180, so that the latter performs the service of returning each slide forward to do the actuating of the counters, owing to the pins 181 of the slides 31 being in the path of forward movement of the bar 180. To prevent the detent bar 180 from being thrown too high, or from being carried back at inopportune times, we provide a post fixed to the base and having a horizontal arm 242 provided with a depending lug or catch 243, said arm and lug being high enough to permit the detent bar to move under it when not raised for re-setting. This prevents the bar 180 from being accidentally carried back when it is raised to permit the pins 181 to pass under it for re-setting. When the bar is not raised, and is being reciprocated to actuate the counters it, of course, slides under the catch 243.

While the above-mentioned application No. 533,443, illustrates and describes mechanism for effecting the raising of bar 180 to permit resetting (said bar having the same reference character in that application), it is sufficient for the purpose of the present application to state that said bar might be raised by hand.

As shown in Fig. 1, the shaft 9^a is formed near one end with an annular groove 245. Said shaft is mounted at its ends to enable it to have a limited longitudinal movement in

its bearings. And as shown in said figure, the racks 200 are made wide enough so that the toothed segments 201 will not be disengaged from said racks when the shaft 9^a is reciprocated.

To reciprocate said shaft we provide a yoke arm 246 having pins engaging the annular groove 245, said arm being carried by a rock-shaft 247 (see Figs. 1 and 3). A spring 248 coiled on the shaft 247, and attached thereto at 249 and at a fixed point 250, normally tends to shift the shaft 9^a toward the left of the machine. To oscillate the rock-shaft 247 and consequently shift the longitudinal position of shaft 9^a, said shaft 247 is provided near its front end with an arm 251 which extends in front of a slide 252 (see Figs. 4, 5 and 6). A latch 253, pivoted at 254 to the top of said slide, has a hook portion which engages a fixed pin 255 when the slide is shifted to the extreme right in such manner that the said slide holds the arm 251 of shaft 247 in the position shown in Fig. 4. To cause the latch to be automatically held in this position, a spring 256 is mounted in a recess in the slide and acts upward against a heel 258 of said latch to cause the hook of the latch to engage fixed pin 255, said latch having also an operating handle 257. Heel 258 extends in such a direction and is so positioned as to limit the movement of its latch and its handle to a point not materially farther than is sufficient to disengage the latch from the pin 255, and still enable said handle to be utilized to shift the slide laterally or toward the left. To guide said slide across the machine, the base 5 is formed with ways or grooves 259 preferably as shown, one in the front surface and one in the top surface. A rib or pin projects from the slide into the front groove and a screw projects downward into the upper groove, a screw being employed for this purpose to facilitate assembling the parts.

To hold the slide 252 in proper position laterally of the machine as hereinafter described, the base 5 is shown as provided with a series of notches 260 adapted to receive a spring detent 261 mounted under said slide.

The slide 252 is provided with a cam projection 262 (see Fig. 1), which cam is adapted to engage any one of the pivoted bars 51 at the left end thereof and to which end the arm 54 is pivoted. It will now be understood that when said slide is in such a position as to oppose movement or oscillation of one of the bars 51, carrying cannot be effected beyond that point or toward the left of the machine.

With the exception of the one at the extreme right of the machine, all of the rocking bars 51 are provided with cam portions 51^a, the outer edge of the cam portion being cut away to form a recess that will provide

- a stop shoulder 51^b. The stop pins 58^a are set in the base far enough in so as to contact with the shoulders 51^b and determine the proper amount of motion that can be imparted to a bar 51. This leaves the outer faces or edges of the bars 51 free to be engaged by the slide 252 when the latter is to be shifted laterally from the position shown in Fig. 1.
- 10 As shown in Fig. 1, the arm 55^a is longer than the arms 55 and is held in proper normal position by a spring 263 which is secured to a post 264. This post 264 performs a further function of serving as a stop for the tooth or projection 55^b projecting beyond the main portion of the arm 55^a and extending to a point alongside of the post 264.

15 The slide 31 for the "cents" group is provided with a shoulder 265 at one side which contacts with the end of the arm 55^a when the parts are in the position shown in said Fig. 1.

20 As has been stated, the method of subtraction by means of addition referred to requires the addition of one cent to the "cents" indications whenever any subtraction at all is to be effected. It is to be understood of course that when any subtraction 25 is to be performed, the slide 252 is moved along the ways to position to prevent movement of a bar 51 at the point necessary to stop carrying farther to the left than the highest value enumerated. This removes 30 the slide from position to obstruct movement of the bar 51 of the "cents" mechanism. Therefore, as soon as the slide 31 of said cents mechanism is carried back at all, the lug 265 recedes from the end of the arm 55^a 35 so that the spring 61 will at once oscillate the bar 51 and cause the arm 54 and its ratchet tooth to rotate the ratchet pinion 45 one tooth. Of course, when said slide 31 returns forward to its normal position and 40 does its own counting, it acts to reset the parts just described owing to contact of the lug 265 with the end of the arm 55^a.

45 As shown in Fig. 1, the co-acting levers that determine the amount of movement 50 that may be imparted to the various slides 31 comprise four members, of which 17^a is the finger key lever pivoted at 106^a and is held upward in normal position by a spring 17^b. The lever 19 is pivoted at 15 and has the pin 20 extending under lever 17^a. The lever 19 also has the pin 29 engaging the lever 27^a, which is also pivoted at 106^a. The 55 fourth member of each group comprises a lever 27^b also pivoted at 106^a, said lever 27^b being provided with a pin 300. The shaft 9^a has a series of pairs of arms 10^a and 10^b, the arms 10^a co-acting with the pins 30 when the shaft 9^a is in the position shown in Fig. 1, and the arms 10^b co-acting with the pins 300 when said shaft 9^a is shifted toward the

right of the machine by mechanism hereinbefore described when subtraction is to be effected. The proportions of the connections and contacting parts of the several groups of levers and arms just described vary in such manner that when the shaft 9^a is in position for addition, the amount of movement that will be transmitted to a slide 31 and therefrom to the proper counter or indicator will be according to the numeral 70 borne by the finger key lever, but when the shaft 9^a is shifted for subtraction, the actuation of the finger key levers by the operator will perform the series of addition 75 according to the well-known method mentioned of obtaining subtraction by addition 80 of the complement of "9."

The finger key lever which carries the disk 16^a in Fig. 1, bearing the symbol 0, when the mechanism is set for addition simply prints a cipher or an "0" and does no adding because the arm 10^a of its group of levers is omitted. The finger key lever which carries the disk 16^b belongs to a group which does no printing at any time. The 90 disk 16^b bears any distinguishing symbol such as a star. Both of these groups are so proportioned and connected that when the mechanism is set for subtraction, the actuation of either will add a nine. 95

In order that actuation of the group having the "star" disk 16^b may space the carriage of the machine, the lever 17 of that group has a movable catch or hook 270 (Fig. 1) which may be swung over the usual space 100 bar (not shown) of the typewriter.

The compound slides 31, 41, constitute 105 actuators for the indicators, and the bar 180 constitutes a combined detent and actuator for the said slides, in the preferred embodiment of our invention. Said bar 180 acts as a detent because of its crossing the slides behind the pins 181 rising from the slides, and it constitutes an actuator because when it is impelled forward under the action of 110 the springs which oscillate the shaft 9^a, it returns to forward position the slides 31, 41, which have been pushed backward by the action of a finger key lever.

If, for any reason, it be desired to hold 115 one or more of the pivoted arms 51 so that it or they cannot swing, slides 266 (see Figs. 1 and 7) may be employed. Said slides are fitted to the ways 259 and adapted to remain inactive at the left of the machine. 120 Each slide 266 has a cam projection 267 so that when moved along to the desired position it will oppose outward swing of the left-hand end of any bar 51. The slide may be shifted along its ways by means of a 125 handle or knob 268.

From the drawings and descriptions given, it will be understood that the number of counting mechanisms is entirely independent of the number of finger key levers, 130

and such counting mechanisms may be increased or reduced any number within the limits of the dimensions of the machine and the requirements of use. This is because any 5 one of the counting or calculating indicators may be coupled with any one of the finger key levers for actuation thereby, through the selective connecting devices.

In the above referred to well-known 10 method of effecting subtraction by adding the complements of nine, the relative values of the key levers for the two calculations are:

15 9 1 2 3 4 5 6 7 8 9 when set for addition,
9 8 7 6 5 4 3 2 1 0 when set for subtraction.

The operator however does not need to 20 know this, and is not liable to be confused by two sets of numerals on the disks of the key levers. As shown in Fig. 1, the key levers bear but one set of numerals.

To set our machine for the operation of subtraction we first move the slide 252 to the left until it is positioned so that its handle 257 is directly in front of the aperture 48, 25 cut in the plate 49, at which the number of the highest denomination in the minuend is visible. The purpose of this is:—1st. To prevent the carrying of a "ten" to the indicator of the next highest denomination. 30 2nd. To allow automatical rocking of shaft 247, and through arm 246, to shift the shaft 9^a laterally to a position whereby the depression of any of the key levers 17, heretofore effecting addition are now in contact 35 with a different set of slotted levers, said new levers being so proportioned that, while they really continue to perform addition, the values of the sums added, instead of being as indicated on their finger disks 16, really 40 add the complements of the figure nine. We then shift the typewriter carriage to such position that if a number were to be added, its indication would appear at the aperture of the highest denomination of the 45 minuend, and proceed as in ordinary addition, except that when no numbers appear to be subtracted, (as represented by the first four number places in the following example), we depress a key, indicated by the 50 star 16^b, said star-key providing the addition of the figure 9, which is the complement of the figure "0", but without the printing of any numeral on the paper.

To illustrate:

55 If the sum of the minuend, as shown by the indicators, is 123,456.78
And the sum of the subtrahend be 78.00

The correct result would be 123,378.78
The actual process is as follows: 123,456.78
To avoid printing zeros, we first depress the star key, which, as stated, adds the complement of a zero, which is nine. 9

60 The carrying to the left being stopped, this first depression indicates the result 023,456.78
The second depression of the star key adds 9

The indicated result is 113,456.78
The third depression of the star key adds 9

65 The indicated result is 122,456.78

The fourth depression of the star key is equivalent to printing a comma, or depressing the space-bar. It steps the carriage but it has no power to change the indicators, as they are not connected for actuation at a point of printing a comma or period.

The last indicated result was 122,456.78 70
The fifth depression of the star key adds 9

The indicated result is 123,356.78

The sixth depression is by the "7" key, (but by its changed connection it adds the complement of 9,) which is 2

The indicated result is 123,376.78 75
The seventh depression is by the "8" key, its changed connection adding 1

The indicated result is 123,377.78

The eighth depression is by the period, stepping the carriage one step.

The ninth depression is by the zero key, not by the star key, because in this position we desire to print the zeros; by its changed connection, it also adds the complement of "0," which is 9. 9

The indicated result is 123,378.68
The tenth depression is by the same zero key, adding as before, 9 9

The final result would be shown on the indicators as 123,378.77 85
But as 1 is automatically added on the cents indicator whenever said indicator is actuated in subtraction, 1

A correct indication of the result is shown as 122,378.78

All these changes occur automatically as 90 rapidly as the operator can make ten hand motions after shifting the slide 252.

The typewritten figures appear on the paper as 123,456.78 78.00 95

The result shown by the indicators is 123,378.78

It will now be readily understood that this structure providing for subtraction by adding the complements of the numeral 9, may be utilized for resetting the indicators to zero, so that all of the zero-setting mechanism described and illustrated may be dispensed with, thus doing away with nearly one-half of the mechanical parts illustrated. 100 This is because, by subtracting the same sum as the one which has been indicated by addition, the results shown by the indicators will be a complete series of zeros. Consequently, if the operator, after adding, shifts the slide 252 as described, and then proceeds to copy 110 the added indications onto the paper in the writing machine, employing the key levers 17 when doing so, the counting mechanisms will be automatically reset to zero, simultaneously with the printing of the total on the sheet. 115

Having described our invention, we claim:

1. A calculating mechanism constructed to effect subtraction by means of addition, 120 said mechanism including a series of counters, actuators for said counters, and shiftable connections to alter the effect of the actuators upon the counters according to whether an added or subtracted result is to 125 be produced, said connections including a series of groups of differently proportioned compound levers.

2. A calculating apparatus comprising a series of indicators, a set of finger keys for 130

- actuating them, and adjustable connections whereby the said set of finger keys may cause the indicators to show the result of addition or the result of subtraction, said connections including a series of groups of differently proportioned compound levers.
3. A calculating apparatus comprising a series of indicators, a set of finger keys for actuating them, and adjustable connections whereby the said set of finger keys may cause the indicators to show the result of addition or the result of subtraction, said connections including a series of groups of compound levers differently proportioned to cause the indicators to exhibit the differences between nine and the numerals of the keys when adjusted for subtraction.
4. A calculating mechanism for adding or subtracting comprising a series of indicators, a series of finger key members each having a single numeral thereon, and shiftable connections whereby any one of the key members may either actuate an indicator according to the numeral borne by said key member or to an amount equal to the difference between that numeral and nine, said connections including a series of groups of differently proportioned compound levers.
5. A calculating mechanism for adding or subtracting, comprising a series of indicators, a series of finger key members each having a single numeral thereon, and shiftable connections whereby any one of the key members may either actuate an indicator according to the numeral borne by said key member or to an amount equal to the difference between that numeral and nine, said connections including a rock-shaft having a series of pairs of arms spaced to permit but one arm at a time to be connected with a finger key member.
6. A calculating mechanism for adding or subtracting, comprising a series of indicators, a series of finger key members, a group of levers for each of said members, the groups having motion-transmitting connections at different distances from their fulcrums, a rock-shaft having a series of pairs of arms, and means for longitudinally shifting said shaft, the arms thereof being spaced to engage one or the other of said pairs with a group of levers.
7. A calculating mechanism for adding or subtracting, comprising a series of indicators, a series of finger key members, a group of levers for each of said members, each group comprising overlapping members one of which has motion-transmitting connections with two others at different distances from their fulcrums, a rock-shaft having a series of pairs of arms, and means for longitudinally shifting said shaft, the arms thereof being spaced to engage one or the other of each pair with one of the said differently connected members.
8. A calculating mechanism for adding or subtracting, comprising a series of indicators, a series of finger key members, shiftable connections whereby said members may actuate the indicators to different amounts, a movable carrying stop for the indicators, and means whereby the position of said stop will automatically set the said shiftable connections for subtraction or addition.

In testimony whereof we have affixed our signatures, in presence of two witnesses.

EDWARD H. PALMER.
WILLIAM S. KINSLEY.
